Inventor.
Marcus De Voursney

Mr. C. C. Beckley of New York, N.Y.
Sellers Patent No. 2,911,016. Filed Oct. 30, 1960.
Design for a breast clasp.

Des 2500

The Schedule referred to in these letters Patent and making part of the same.

to all whom it may concern:

I
Be it Known that I, Marcus De Vries, citizen of the City
of New York, have invented a new and improved
Design for Crack-dam, and do hereby declare that the following is a full
clear, and exact description thereof which will enable others skilled in the art
to make and understand the same, reference being had to the accompanying drawing
forming a part of this specification in which:

Figure 1 represents a front elevation of this invention.

Figure 9. West side elevation of the tower.

Figure 3 is a horizontal section of the tunnel.

Similar letters of reference indicative like past.

This invention relates to a Design the principal features of which consist in segmental and angular reflecting surfaces in the front glass and a series of reflecting surfaces in the interior of the lamp shade in a corresponding series of flat reflecting surfaces on the outside of the glass part in the piece of the lamp.

A. represents the front glass of my lamp, in which it is secured in the frame.
B., in the ordinary manner. This glass is provided with a series of crenament, or reflecting surfaces, which alternate with angular reflecting surfaces, as shown in figure 1.

One side of the lamp is provided with a glass B' which is made polygonal so as to present a series of flat reflecting surfaces C , and the interior of the lamp opposite to the side glass B' provides a series of reflecting surfaces d . By this means a lamp is obtained which presents an elegant appearance and the brilliancy of which at night is materially enhanced by the various reflecting surfaces.

What I claim is, a new, and device to secure by patent it,

the Design for a Coach Lamp as shown and described.

The above specification of my invention signed by me this 29th day of September 1866. .
